UNITED STATES PATENT OFFICE.

LOUIS V. ARONSON, OF NEWARK, NEW JERSEY.

COMBINATION-WRENCH.

995,837.

Specification of Letters Patent. Patented June 20, 1911.

Application filed November 29, 1909. Serial No. 530,309.

To all whom it may concern:

Be it known that I, LOUIS V. ARONSON, of the city of Newark, county of Essex, and State of New Jersey, have invented certain new and useful Improvements in Combination-Wrenches; and I do hereby declare the following to be a full, clear, and exact description thereof, reference being had to the accompanying drawings, forming a part of this specification.

My invention relates to adjustable tools and consists in a combination wrench composed of two or more wrench blades adjustable upon each other and capable of being rigidly secured to each other in position for use through the simple means as hereinafter particularly described and claimed.

The object of my invention is to provide a compact portable combination wrench containing two or more wrench blades to fit different sized nut heads, wherein the blade desired to be used may be withdrawn from the gang and adjusted in the line of the other blades which operate as a handle.

By this construction, I secure not only a compact portable pocket wrench capable of fitting various sized nuts, but also one in which the wrench blades not in use operate as a handle for the one in use, securing increased leverage.

By my improved construction, when the wrench blade is properly adjusted, it is impossible for it to slip upon the other blades and further, when the clamp is released, the respective blades permit of the desired ready adjustment to any position.

In the accompanying drawings, Figure 1 is a plan view of my improved combination wrench. Fig. 2 is a side view of the same. Fig. 3 is a sectional view taken on line $x-x$ of Fig. 1.

Referring now more particularly to the drawings, wherein like characters of reference refer to similar parts in the several views, *a*, *b*, *c* and *d* indicate four wrench members which are adapted to lie flat one upon another and each of which is provided with enlarged head portions and a parallel faced handle part connecting said enlarged head portions, the handle parts of all of said members being of uniform width. The several wrench members are secured together by an open U-shaped strap or yoke *e* which closely embraces the handle parts of all of said members but permits their free transverse insertion in the yoke in assem-

bling the tool, the side walls of said strap lying in close proximity to the parallel edges of the handle parts of the wrench members and projecting above the face of the topmost wrench member. Journaled in the upper portion of the side walls of the strap or yoke *e* is an eccentric *f* which serves to clamp all of the wrench members tightly together and hold the same against any movement with respect to each other. The eccentric is provided with an operating handle *g* and by loosening the eccentric by means of such handle, any one of the wrench members may be readily adjusted upon the other wrench members and either fully extended, as shown in dotted lines in Fig. 2, or partially extended and then secured.

By the use of yoke *e* in combination with the peculiar form of the wrench members having enlarged heads and a reduced portion connecting said heads, it will be apparent that while any of the wrench members may be readily brought into use, it will be impossible for any of the wrench members to become disengaged from the strap. It will also be apparent that by the use of a coupling member of the character of the yoke *e*, the wrench members are held firmly against independent lateral movement and that the construction is such that the removal of any one of the wrench members is permitted, should it be necessary to replace the same or straighten a wrench blade if the same should be slightly twisted.

I claim:

1. A combination wrench comprising a plurality of independently sliding members having enlarged heads at their opposite ends and similar parallel faced handle parts, an open U-shaped strap closely embracing the handle parts of said wrench members and extending above the topmost wrench member, and an eccentric journaled in the side walls of the strap and adapted to engage the topmost member to clamp the parts against any movement with respect to each other, as set forth.

2. A combination tool comprising a series of blades with straight parallel sides and enlarged ends each provided with a tool at each end and adapted to slide longitudinally upon each other, whereby either end of any blade may be projected into operative position, and means for clamping the blades together in any position comprising an open yoke or holder and a cam pivoted

in said holder and provided with a hand lever operable either forwardly or rearwardly with reference to the tool projected for operation.

- 5 3. A combination tool, comprising a series of blades with straight parallel sides and enlarged ends, each provided with a tool at each end and adapted to slide longitudinally upon each other, whereby either 10 end of any blade may be projected into operative position and means for clamping the blades together in any position comprising an open yoke or holder adapted to receive 15 said blades and contact with said parallel sides, the ends of the yoke projecting beyond the blades, transversely, and a cam

pivoted in the ends of said yoke, said cam being provided with a hand lever and the pivot of the cam head being located in the longitudinal center of the cam head and lever and nearer to the end of the cam head than to either side thereof, whereby when said cam lever is turned against the blades in either direction, the cam head will be brought into position to securely clamp the 25 blades together.

This specification signed and witnessed this 27th day of November, 1909.

LOUIS V. ARONSON.
